UNITED STATES PATENT OFFICE.

MAX RACHLIN, OF NEW YORK, N. Y.

GUTTER HANGER.

Application filed March 7, 1923. Serial No. 623,413.

To all whom it may concern:

Be it known that I, MAX RACHLIN, a citizen of Russia, and resident of the city of New York, in the county of Queens and State of New York, have invented certain new and useful Improvements in Gutter Hangers, of which the following is a specification.

The present invention relates to gutter hangers, that is to say to devices for supporting roof gutters.

The main object of the invention is to provide a gutter-hanger, which is extremely simple in construction, durable in use and capable of manufacture on a commercial scale, or in other words one which is not so difficult to make as to be beyond the reasonable cost of such a contrivance.

Another object of the invention is to produce a gutter-hanger that is obtained by stamping operations, means being provided for effectively strengthening the sheet metal strap portions, of which the hanger is composed.

A further object of the invention is to so design the gutter-hanger that the gutter may be adjustably mounted on the roof or wall of the building.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the several parts and details of construction within the scope of the appended claims, without departing from the spirit or sacrificing any of the advantages of the invention.

One of the many possible embodiments of the invention is illustrated in the accompanying drawings, in which:

Figure 1 is a side elevation, partly in section, of a gutter-hanger constructed in accordance with the present invention, the gutter being shown in position thereon;

Fig. 2 is a section taken on line 2—2 of Fig. 1, Fig. 3 is a section taken on line 3—3 of Fig. 1, on a larger scale; Fig. 4 is a front elevation of a portion of the gutter-hanger and a portion of the gutter shown in Fig. 1, Fig. 5 is a section taken on line 5—5 of Fig. 4, Fig. 6 is an eleva-

tion similar to the one shown in Fig. 1, the gutter-hanger being directly fastened to the building; Fig. 7 is a view similar to the one shown in Fig. 6, illustrating another way of directly fastening the hanger to the building wall; Fig. 8 is a side elevation of a bracket for co-operation with the hanger shown in Figs. 1, 6 and 7, Fig. 9 is a top plan view of the bracket shown in Fig. 8, Fig. 10 is a side elevation showing the application of a bracket illustrated in Figs. 8 and 9, Fig. 11 is a similar elevation, the bracket being used in another position; and Fig. 12 is a section taken on line 12—12 of Fig. 11.

Referring now first to Figs. 1 to 5, inclusive, of the drawings, the gutter embracing strap 60 comprises a curved sheet metal strip, which is substantially U-shaped in transverse cross-section, it including a web 61, that is curved so as to abut against the underface of the roof gutter 30, and two vertically extending flanges 62, which serve to strengthen the said web. In order to further strengthen the web, it is provided with a longitudinal depression 63, extending between the flanges, a hole 64 being formed in the said depression to prevent water from collecting therein. The flanges 62 are provided adjacent their inner ends each with a vertical row of apertures 65, the members of one row registering with those of the other, for a purpose herein-after to be described. Adjacent the said inner end, there is formed in the web 61 an outwardly projecting lug 66, engaging the inner plain edge 32 of the gutter. With the bead 31 of the gutter is brought into engagement a sheet metal strip 67, having in its inner end a slot 68, through which is extended a projection 69, the latter being formed adjacent the outer end of the web of the gutter strap. The strip 67 is bent over the said bead, after the gutter has been placed in position on the strap.

The gutter embracing straps are engaged with brackets 70, which are nailed or otherwise secured to the roof structure 33. These brackets comprise each a plane section 71, abutting against the upper face of the roof, and a vertically extending section 72 that is substantially U-shaped in transverse cross-section and fits into the inner end of the gutter embracing strap. A rib 73 is formed at the junction point of the sections 71 and 72, to strengthen the bracket. In the vertical

section 72 of the bracket are formed two vertical rows of apertures 74, which are adapted to be brought into register with with apertures 65 in the strap 60.

5 After the brackets have been mounted on the roof, the straps 60 are shifted into the desired position relative to the brackets, bolts 75 being passed through registering apertures in the straps and brackets. The 10 gutter is then placed onto the straps and fixed thereto.

15 The modification shown in Fig. 6 of the drawings differs from the one above described in that the gutter straps are directly fastened to the building wall. In order to 20 permit the gutter straps to be fastened to the face-board 76 on the building wall, the substantially vertical portion of the web 61 of the gutter embracing strap is provided with a row of holes 77, through which nails 25 or screws 78 may be driven into the said face-board.

25 The gutter strap may also be directly fastened to the roof beams 79, as shown in Fig. 7 of the drawings, in which case one or more nails or screws 80 are driven through registering apertures 65 in the flanges 62 of the gutter strap into the said beam.

30 Instead of the bracket above-described, the bracket shown in Figs. 8 and 9 of the drawings may be made use of. This bracket comprises a plate member 81, having holes 35 82, through which fastening means, such as screws 83 may be passed either into a roof beam 84, as shown in Fig. 10 of the drawings, or into a face-board 85, as shown in Fig. 11 of the drawings. With this plate member is made integral a vertically extending outwardly projecting bar portion 86, that is U-shaped in transverse cross-section and fits between the webs 62 of the gutter 40 embracing strap 60. The bar portion 86 is provided with two vertical rows of apertures 87, for co-operation with the apertures 65 45 in the web 62 of a gutter embracing strap. Screws 88 are passed through the gutter em-

bracing strap and the bar portion 86 of a bracket, to hold the said strap in position on the said bracket. It is to be noted that, when it is to be attached to a roof beam 84, the 50 bracket may be fastened to either vertical face thereof, that is to say it is unnecessary to make right-side and left-side brackets. The brackets are made by a stamping operation from sheet metal. 55

From the foregoing it appears that all of the elements of the gutter hanger herein described are made of sheet metal, the gutter embracing straps being provided with strengthening means, made integral therewith, the strengthening means preventing the said straps from being deformed by the weight of the gutter resting thereon. It also appears that the gutter embracing straps may be adjustably secured to the roof or 60 wall of the building, either by the aid of or without attaching brackets. All of the constructions herein described are extremely efficient in construction, and are capable of being conveniently mounted on the building. 70

It is to be observed that in the constructions shown the outer end of the gutter embracing strap is extended into the bead of the gutter. The purpose of this arrangement is to prevent transverse shifting of the 75 gutter on the embracing straps.

What I claim is:—

A gutter-hanger including a gutter embracing strap made of a single sheet of metal and having a substantially U-shaped transverse cross-section throughout its length, the web portion of the U-shaped cross-section being provided with a depression throughout a substantial portion of the strap to provide a strengthening rib, said depression being provided with a hole to permit egress of water from and ingress of air into said depression. 80

Signed at New York, in the county of New York and State of New York, this 5th day 90 of March A. D. 1923.

MAX RACHLIN.
